UNITED STATES PATENT OFFICE

CHRISTOPHER WILMANNS, OF INDIANAPOLIS, INDIANA, ASSIGNOR TO LIBERTY ELECTRIC COMPANY

SMOKER'S STAND

Application filed April 25, 1928. Serial No. 272,784.

My invention relates to an improved construction and arrangement of smokers' stands or ash trays of the type adapted to stand upon the floor by a chair or the like; for the convenient use of smokers; and it consists in certain improvements whereby such a device is provided with a removable tray which can be easily kept clean and sanitary, which will not become discolored or marred by the fire from the ashes or butts of cigars or cigarettes and at the same time will be capable of receiving discarded ashes, butts and the like so that they will not be exposed to view and the device thus maintained in an attractive and desirable condition at all times, all as will be hereinafter more fully described and claimed.

Referring to the accompanying drawings which are made a part hereof and on which similar reference characters indicate similar parts,

Figure 1 is a side elevation partly in section of a smoker's stand illustrating one application of my invention.

Figure 2, a perspective of the removable glass top shown in Fig. 1.

Figure 3, a perspective of a modified form of top constructed of metal but having a two part glass tray.

Figure 4, a further modified form of top constructed of metal but having a one-piece glass tray.

Figure 5 is a vertical section of a modified form of base showing the same resting upon the floor with the removable receptacle broken away, and

Figure 6 is a similar view showing the device held in elevated position and illustrating the operation of the retaining fingers.

As shown in Figures 1 to 4 of the drawings, the stand comprises a hollow base 10, a hollow stem 11 and a tray or receptacle 12 mounted on top of said stem.

The base 10 and stem 11 are preferably formed of hollow metal construction, said base being provided with a thickened or weighted bottom portion 13 having a flat under surface to prevent it from tipping over and maintain the stand in upright position. The base is provided with an opening in its top which is surrounded by an upstanding

flange or collar 14 adapted to fit into the enlarged cup 15 on the lower end of the stem 11, the flange on the base being provided with spirally arranged external ribs 16 which co-operate with similar internal ribs 17 on the cup 15 on the lower end of the stem for fastening the base and stem together. The upper end of the stem 11 is also provided with an enlarged funnel or cup-shaped portion 18 having spiral grooves or thread sections 19 on its interior for engaging and holding a tray or top therein.

The tray or top is formed of glass and, as shown in Fig. 1, has a central opening surrounded by a tapered depending flange 20 of a size to fit snugly within the cup-shaped portion 18 of the upper end of the stem providing a glass lining for the metal cup and a glass receptacle or tray for the ashes, cigar and cigarette butts and the like. Said tray is provided with a substantially cylindrical external portion 21 where the tapered flange joins the tray and such portion is provided with spiral ribs 22 which co-operate with the grooves or thread sections in the cup on the upper end of the stem for fastening the tray and stem together.

The glass tray 12 is provided with an upstanding marginal flange 23 adapted not only to retain the ashes and the like deposited in the tray, but also serves as a means for removing the ashes from a burning cigar or cigarette. The flange 23 is also provided with thickened recessed portions 24 which serve as rests for the cigars and cigarettes.

The tray 12 is provided on one side with an upstanding flange 25 adapted to fit snugly within the outer jacket of a conventional match box and having a curved inner face 26 for co-operation with a complementarily curved upstanding flange 27 which together form a socket for the reception of the base of an electric cigar lighter 28. Also the flanges 25 and 27 are spaced in a manner to accommodate between them a packet of matches, thus adapting this part of the tray to hold either a match box, a packet of matches or an electric cigar lighter whichever may be preferred and interchangeable one with the other.

The stand may be provided with any desired ornamentation to render the same attractive in appearance and the glass tray or top section may be etched or otherwise ornamented.

The central depending circular flange 20 which extends down into the cup or socket in the top of the stem not only affords protection against heat to the metal but also since it is transparent permits the color and ornamentation on the interior surface of the metal cup to be readily seen therethrough as this is one of the important features for the interior of the cup is preferably given bright colors to increase its ornamental appearance.

In Figs. 3 and 4 I have shown modified forms which comprise metal trays 29 and 30 provided with central openings about which are formed circular flanges 31 and 32 which are adapted to have their lower ends pressed over the upper end of the stem 11 for uniting the parts. The trays are preferably stamped so that they have upstanding marginal rims or flanges 33 and 34 with flared depending skirts, said marginal flanges being provided with flattened depressions 35 and 36 forming rests for cigars and cigarettes.

As shown in Fig. 3, a strap 37 may be attached to the tray to form a handle by means of which it may be carried about, a socket member 38 being attached to the center of the handle, such socket member being adapted to interchangeably support a match box or cigar lighter in a manner similar to that shown in Fig. 2. If desired, the handle may be omitted and the socket member attached directly to the tray as shown in Fig. 4. In either case, however, I preferably provide a glass lining for the trays, two sections 39 being necessary for the modification shown in Fig. 3, and one section 40 being necessary for the tray shown in Fig. 4, the last mentioned section however being provided with a recess 41 to accommodate the socket member 38.

Referring to Figures 5 and 6 I have shown a hollow cast iron base 42 attached to the lower end of a hollow stem 43, said base being provided with an open lower end and having a detachable or removable waste chamber or receptacle 44. The receptacle 44 is held in place by a pair of opposed retaining fingers 45 which extend through spring casings 46 and are held in outwardly projected position by means of springs 47 which bear against collars 48 on the horizontal portion of the spring fingers 45. The spring casings or housings 46 extend through the wall of the base 42 and are in convenient location to be readily manipulated by pressing on knobs 49 on the outer ends of the spring fingers. With this construction, when the knobs 49 are pressed the spring fingers are located substantially close together to permit their hook portions 50 to pass freely

through the mouth 51 of the waste chamber to permit the ready removal of the same when it is desired to empty its contents. In order, however, to prevent the waste chamber from being accidentally released from its position within the base 42 I make the waste chamber and the base of close fitting construction, so that in order to release the waste chamber it is necessary to press the knobs 49 for contracting the spring fingers when the device is resting upon a flat surface. The waste chamber therefore cannot be released except in this position.

In replacing the waste chamber it is only necessary to place the stand over the said waste chamber when the springs 47 will yield and the spring fingers will snap into place through the mouth of the receptacle 44, thus automatically accomplishing the coupling action without requiring any specific manual operation.

These and other modifications may be substituted for that shown in Fig. 1 without departing from the spirit of the invention which consists in providing a metal base and stem with a top of glass whereby such a device is provided which is not only more durable and protected against deterioration by use, but also adds materially to its attractiveness as an article of furniture.

It will be obvious to those skilled in the art that various changes may be made in my device without departing from the spirit of the invention, and I, therefore, do not limit myself to what is shown in the drawings and described in the specification, but only as set forth in the appended claims.

Having thus fully described my said invention, what I claim as new and desire to secure by Letters Patent, is:

1. A smoker's stand comprising a hollow base, a detachable waste receptacle carried by said base, and means connecting the base and receptacle operable for releasing the receptacle from the base only when the receptacle is supported in a substantially horizontal position, substantially as set forth.

2. A smoker's stand comprising a hollow base, having an open bottom, a waste receptacle in said base removable through said open bottom, means detachably connecting said base and receptacle, said means being adapted to release the receptacle only when the bottom of the receptacle is in substantially parallel relation to the bottom of the base, substantially as set forth.

3. A smoker's stand comprising a hollow base, having an open bottom, a waste receptacle in said base removable through said open bottom, means detachably connecting said base and receptacle, said means comprising spring fingers projecting through the side of the base in a position to be manually operated, and means urging said spring fingers apart, substantially as set forth.

4. A smoker's stand comprising a hollow base, having an open bottom, a waste receptacle in said base removable through said open bottom, means detachably connecting said base and receptacle, said means comprising housing extending outwardly through the walls of the base, spring fingers extending through said housings and provided with manipulating extremities, collars on each of said spring fingers within said housings, and means in said housings engaging said collars and urging said spring fingers apart, substantially as set forth.

10 In witness whereof, I have hereunto set my hand at Indianapolis, Indiana, this 5th day of March, A. D. nineteen hundred and twenty-eight.

CHRISTOPHER WILMANNS.
